(57) **CLAIM**

The ornamental design for a bus shelter, as shown and described.

DESCRIPTION

FIG. 1 is a perspective view of the bus shelter;

FIG. 2 is a top view of the bus shelter shown in FIG. 1;

FIG. 3 is a front view of the bus shelter shown in FIG. 1;

FIG. 4 is a bottom view of the bus shelter shown in FIG. 1;

FIG. 5 is a back view of the bus shelter shown in FIG. 1;

FIG. 6 is a right side view of the bus shelter shown in FIG. 1; and,

FIG. 7 is a left side view of the bus shelter shown in FIG. 1. The broken line showing in the figures is for illustrative purposes only and forms no part of the claimed design.
